US00D996902S

(12) **United States Design Patent** (10) **Patent No.:** **US D996,902 S**
(45) **Date of Patent:** **** Aug. 29, 2023**

(54) **CONTAINER WITH A LID**

(71) Applicant: **Clarity, Inc.**, Los Angeles, CA (US)

(72) Inventor: **Glenn Tobias**, Los Angeles, CA (US)

(73) Assignee: **CLARITY, INC.**, Los Angeles, CA (US)

(**) Term: **15 Years**

(21) Appl. No.: **29/722,025**

(22) Filed: **Jan. 24, 2020**

(57) **CLAIM**

The ornamental design for a Container with a Lid as shown.

DESCRIPTION

FIG. 1 is a perspective view of a Container with a Lid showing my new design;

FIG. 2 is a side view thereof;

FIG. 3 is a front view thereof;

FIG. 4 is a top view thereof;

FIG. 5 is a perspective view of a Container with a Lid in its open position;

FIG. 6 is a side view thereof;

FIG. 7 is a front view thereof; and,

FIG. 8 is a top view thereof.

1 Claim, 8 Drawing Sheets
